UNITED STATES PATENT OFFICE.

THOMAS B. ROSS, OF EVANSVILLE, INDIANA.

SASH-FASTENER.

SPECIFICATION forming part of Letters Patent No. 319,324, dated June 2, 1885.

Application filed December 4, 1883. (No model.)

To all whom it may concern:

Be it known that I, THOMAS B. ROSS, a citizen of the United States, residing at Evansville, in the county of Vanderburgh and State 5 of Indiana, have invented certain new and useful Improvements in Window-Fasteners, of which the following is a specification, reference being had therein to the accompanying drawings.

10 This invention relates to improvements in window-fasteners, and has for its object to lock the sash in any position in which it may be placed, and thus prevent the sash from being either raised or lowered; and it consists, 15 essentially, in combining a gravitating locking-pawl and an operating bell-crank lever with a gear-wheel mounted in a box located in the window-casing, and adapted to engage a rack-bar attached to the adjacent edge of 20 the window-sash.

Figure 1 is a front elevation of a window-frame and sash provided with this attachment. Fig. 2 is a view of the sash removed from the frame, and shows some of the parts of the 25 fastener in detail. Fig. 3 is an edge view of a portion of the window-frame with a part broken away, and shows the construction of the fastener. Fig. 4 is a detail view of a modified form of the device for unlocking the 30 fastener.

The letter A indicates the window-frame. B is the sash. E is a rack-bar secured thereto, and K a spring on the opposite side thereof.

35 C is a metal plate secured to the window-frame, and has lugs c, to which is pivoted the horizontal arm of the bell-crank lever D, to the portion D' of which is attached a button, a, the outer surface of which protrudes slightly 40 through the plate C, as shown in Figs. 1 and 3. The end of the arm D may be reduced, so as to enter openings g in the plate or rod of the gravitating locking-pawl G, which is provided with a head, G', and a locking-stud, g, 45 which, when the fastener is to be locked, enters between two of the teeth of the spur-wheel H through a suitable opening in the top of the box F. The plate or rod passes through a suitable guide or guides attached to the box

F, and the specific gravity of the pawl causes 50 its head G' to rest upon the top of the box F, and when in this position the fastener is locked, as the wheel H is thereby prevented from turning on its axis; but if pressure is applied to the button a the inner end of the arm D is 55 raised, together with rod G, its head G', and locking device g, and by this means the spur-wheel H is released and is permitted to revolve freely when engaged by the teeth of the ratch-bar E as the sash B is either raised or 60 lowered.

K is a spring attached to one side of the sash, and is intended to force the sash and the teeth of the rack-bar against and into the teeth of spur-wheel H, and thereby provide against 65 the swelling or shrinkage of the wood-work.

This sash-fastener is to be used either on car or house windows.

I desire to observe that I am aware that it is not broadly new to provide a window-sash 70 with a rack-bar on one side and to locate within the window-casing a box carrying a gear-wheel and a locking-pawl, the gear-wheel being adapted to intergear with the rack and the pawl with the gear, for the purpose of 75 holding the sash at varying heights, and that I do not, therefore, broadly lay claim to such.

Having described my invention, what I desire to secure by Letters Patent, and claim, is—

1. In a sash-fastener, the combination, with 80 the window-frame provided on one side with a pressure-spring and on the other side with a rack-bar, of a box located within the window-casing, and carrying a gear-wheel which meshes with said rack, the gravitating sliding 85 locking-pawl having a weighted head and a projecting stud, and the pivoted bell-crank lever connected at one end with said gravitating pawl, and provided at the other with a button which slightly protrudes beyond the 90 surface of the casing.

2. In a sash-fastener, the combination, with 95 the box and the gear-wheel mounted therein, of the sliding gravitating locking-pawl provided with a weighted head and a projecting stud, which engages normally with the teeth of said gear and with a series of apertures, and the pivoted bell-crank lever engaging at

one end with said apertures and provided at the other with a button.

3. In a sash-fastener, the combination, with the sliding gravitating locking-pawl having a series of apertures in one of its members, a weighted head, and a projecting stud, of the bell-crank lever, one end of which is adapted to engage said apertures, and the other of which is provided with a button.

In testimony whereof I affix my signature in presence of two witnesses.

THOMAS B. ROSS.
